UNITED STATES PATENT OFFICE

HENRY C. STOLL, OF BRONX, NEW YORK

DESIGN FOR CIGARETTE BOX OR THE LIKE

Application filed March 31, 1930. Serial No. 35,073. Term of patent 3½ years.

To all whom it may concern:

Be it known that I, HENRY C. STOLL, a citizen of the United States, residing at Bronx, county of Bronx, and State of New York, have invented a new, original, and ornamental Design for a Cigarette Box or the Like, of which the following is a specification, reference being had to the accompanying drawing, forming part thereof.

The single figure is a perspective view of the cigarette box showing my new design, the rear side of the article shown being plain.

What I claim is:

The ornamental design for a cigarette box or the like substantially as shown and described.

HENRY C. STOLL.
